UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,458, dated September 13, 1881.

Application filed August 9, 1881. Term of patent 3½ years.

To all whom it may concern:

Be it known that I, HENRY HORAN, of East Orange, in the county of Essex and State of New Jersey, have invented a new and original Design for Carpets, of which the following is a specification.

This invention relates to a new and original design for carpets and similar fabrics; and it consists in the novel grouping and configuration of figures, hereinafter more fully described.

The accompanying photograph represents a face view of a carpet having my new design.

The entire groundwork of the carpet is cov-

ered with a mass of various leaves and flowers and their stems. There are water-lily leaves, ferns, maple-like leaves, interspersed with flowers, giving to the eye the impression of a thick hedge, through which the rays of light can hardly find their way.

I claim—

The design for carpets, substantially as shown.

HENRY HORAN.
